(57) **CLAIM**

The ornamental design for a dispenser, as shown and described.

DESCRIPTION

FIG. 1 is a top, front, right side isometric view of a dispenser, of embodiment one, showing my new design; FIG. 2 is a front elevation view of the dispenser shown in FIG. 1;

FIG. 3 is a rear elevation view of the dispenser shown in FIG. 1;

FIG. 4 is a right side elevation view of the dispenser shown in FIG. 1;

FIG. 5 is a left side elevation view of the dispenser shown in FIG. 1;

FIG. 6 is a top plan view of the dispenser shown in FIG. 1;

FIG. 7 is a bottom plan view of the dispenser shown in FIG. 1;

FIG. 8 is a top, front, right side isometric view of a dispenser, of embodiment two, showing my new design; FIG. 9 is a front elevation view of the dispenser shown in FIG. 8;

FIG. 10 is a rear elevation view of the dispenser shown in FIG. 8;

FIG. 11 is a right side elevation view of the dispenser shown in FIG. 8;

FIG. 12 is a left side elevation view of the dispenser shown in FIG. 8;

FIG. 13 is a top plan view of the dispenser shown in FIG. 8; and,

FIG. 14 is a bottom plan view of the dispenser shown in FIG. 8.

The broken lines in the figures illustrate environmental subject matter that form no part of the claimed design. The dot-dash broken lines of FIGS. 1, 3-6, 8, and 10-13 immediately adjacent to the claimed areas in the views represent the boundaries of the design and form no part thereof.
